GEORGE B. CADY, OF CANASTOTA, NEW YORK.

DEVICE FOR OPENING AND CLOSING WIRE LINK LOOPS AND THE LIKE.

Application filed January 11, 1927. Serial No. 160,404.

This invention relates to a device for opening and closing wire link loops and analogous objects, such, for example, as those used on the ends of cross chains for attachment to the side chains of automobile tires.

Owing to the excessive wear and strain upon the tread links of the cross chains they become broken or otherwise impaired after a reasonable period of use and necessitate replacement which requires the opening and closing of the hook shaped ends of the end links to permit them to be removed and replaced from and upon the side chains, and the main object of the present invention is to provide a more efficient and expeditious means for opening and closing these end links than has heretofore been practised.

Another object is to provide the device with a suitable rest or limiting stop adjustable at will for registering the portions of the links to be operated upon with the link-spreading and closing jaws.

Other objects and uses relating to specific parts of the device will be brought out in the following description.

In the drawings:

Figure 1 is a perspective view of a device for carrying out the objects stated.

Figure 2 is an enlarged longitudinal vertical sectional view of the same device taken on line 2-2, Figure 1.

Figure 3 is a transverse vertical sectional view taken on line 3-3, Figure 1.

Figure 4 is a horizontal sectional view taken in the plane of line 4-4, Figure 2.

As illustrated, this device comprises a main supporting frame consisting, in this instance, of a base section 1 and cap sections 2 and 3, the base section being provided with end extensions 4 having bolt holes 5 for receiving suitable clamping bolts by which the base section may be firmly secured to a bench or other work-table.

The underside of the base section 1 is provided with a chamber 6 wholly within the marginal edges thereof to allow the lower flat faces of the extensions 4 to rest flatwise from the surface of the bench or table and also to permit the adjustment of a suitable rest or limiting stop herein-after described.

The upper portion of the base section 1 is provided with chambers 7 and 8 extending from side to side thereof and

forming similar upright standards 9, 10 and 11 in longitudinally spaced relation.

The upper sides of the standards 9 and 10-11 are provided with longitudinally extending guide openings 13, 14 and 15 extending through the upper faces thereof and in longitudinal alignment but are normally closed by the cap sections 2 and 3 extending across the upper sides of the openings and firmly secured to the upper faces of the posts 9, 10 and 11 by screws 16 or equivalent fastening means, the rear side 2' of the plate being extended rearwardly and downwardly across the rear end of the lever and fulcrum bearing therefor to protect the user against contact with the moving parts.

The openings 13, 14 and 15 constitute guide-ways for receiving a pair of opposed jaws 17 and 18, the jaw 17 being relatively longer than the jaw 18 and slideable endwise in the guide openings 13 and 14 while the other jaw 18 is relatively short and is held in the corresponding opening 15 against endwise movement by a locking pin 19 which is seated in a socket 19' in the adjacent post 11 and enters an aperture 18' in the jaw 18 thereby holding the jaw 18 in fixed relation to the frame section 1 and cap section 3.

These cap sections 2 and 3 serve to hold the jaws 17 and 18 against upward displacement and form the upper walls of the guide openings 13, 14 and 15 but may be removed by removing the screws 16 to permit the removal and replacement of the jaws when desired.

The jaw 17 is reciprocally movable endwise in the guide openings 13 and 14 across the chamber 7 and toward and from the jaw 18 and is adapted to be operated by a hand lever 20 which extends transversely through the chamber 7 directly beneath the jaw 17 and has its rear end fulcrumed between and against opposed shoulders 21 of an opening 22 in the rear side of the base section 1.

The intermediate portion of the lever 20 is pivotally connected to the intermediate portion of the sliding jaw 17 by means of a pivotal screw 23 for re-

ciprocating said jaw —17— endwise as the lever —20— is rocked in reverse directions.

The front end of the lever —20— is provided with a socket —24— for receiving one end of a handle —25— shown by dotted lines in Figure 4, said handle being of any desired length to obtain the required power for operating the jaw —17— toward the jaw —18— for producing the required spreading or closing of the loop or link as —a—.

The rear end of the lever —20— is slidable endwise in the opening —22— and between the jaws —21— to compensate for its changing position as its pivot —23— is moved rectilinearly, the movement of said lever being limited by engagement with the inner end faces as —26— of the posts —9— and —10— as shown in Figure 4.

A screw —27— is engaged in a threaded aperture —28— in the base section —1— between the posts —10— and —11— and is provided with a knurled head —29— projecting into the chamber —8— below the meeting ends of the jaws —17— and —18— to form an adjustable rest or limiting stop for the loops —a— to be operated upon and to hold the portions of the loops in proper position for engagement by the adjacent ends of the jaws —17— and —18—.

The lower and upper faces of the inner ends of the jaws are beveled at —30— to form knife edges in horizontal alinement with each other for entrance between opposite sides of the closed loop to spread the same when the jaws are brought together and the loop is placed in the position shown in Figure 2 or for closing the opposite sides of the open loops when placed in the position shown in Figure 4.

It will be observed that the inner ends of the jaws —17— and —18— are tapered rather abruptly, the object of which is to cause a quick spreading of the closed loops and to prevent injury to the opposite sides of the loops when the jaws are used to close the loop.

Operation.

When it is desired to open a closed loop the rest —29— will be adjusted so that when the loop is placed edgewise thereon as shown in Figure 2 the meeting edges of opposite sides of the loop will be registered with the inner tapered ends of the jaws —17— and —18— so that when the jaws are brought together the tapered ends thereof will enter between the opposite sides of the loop and quickly spread the same.

On the other hand, when it is desired to close an open loop the latter will be placed upon the rest —29— between the adjacent ends of the opposed jaws —17— and —18— with the opposite sides of the loop facing the tapered ends of the jaws whereupon the proper operation of the lever —20— will

bring the jaws toward each other to close the loop.

These operations are particularly simple and expeditious and enable the user to remove and replace the cross chains without material loss of time thereby greatly reducing the expense of these repairs, and materially increasing the output for any given period of time without excessive labor on the part of the operator. 75

In case it should be necessary to remove the jaws for any reason the cap sections —2— and —3— may be quickly removed by simply removing the screws —16— whereupon the jaws may be lifted vertically from their respective guide openings —13— and —14— and —15— without displacing the lever —20— from the jaw —17—, it being understood that the opening —22— for the rear end of the lever —20— is open at the top to permit such removal and that the locking pin —19— will remain in the socket —19'—.

This device is also useful in cutting the wire links of the side chains and other analogous uses and, therefore, the invention is not limited to spreading and closing of the attaching links of the cross chains. 90

What I claim is:—

1. A device for opening and closing wire loops and the like comprising a base section having transverse openings in longitudinally spaced relation and lengthwise guide openings some distance above the bottoms of the transverse openings, a jaw mounted in one of the guide openings, and provided with a tapered inner end projecting into the adjacent transverse opening, an additional jaw slidable endwise in the other guide opening and provided with an inner tapered end movable toward and from the first-named jaw, and means extending into the other transverse opening for reciprocating the second-named jaw. 95

2. A device for opening and closing wire loops and the like comprising a frame having transverse openings and lengthwise openings some distance above the bottoms of the transverse openings, opposed jaws mounted in the lengthwise openings and having their adjacent ends tapered toward each other and projecting into one of the transverse openings, means for holding one of the jaws against endwise movement, and a hand lever extending into the other transverse opening and operatively connected to the other jaw for reciprocating the same toward and from the first-named jaw. 110

3. A device for opening and closing wire loops and the like comprising a frame having transverse openings and lengthwise openings some distance above the bottoms of the transverse openings, opposed jaws mounted in the lengthwise openings and having their adjacent ends tapered toward 120

each other and projecting into one of the transverse openings, means for holding one of the jaws against endwise movement, and a hand lever extending into the other trans- 5 verse opening and operatively connected to the other jaw for reciprocating the same toward and from the first-named jaw, and a supporting member for the loop mounted on the frame and adjustable toward and 10 from the adjacent end of the jaws.

4. A device for opening and closing wire loops and the like comprising a frame having transverse openings and lengthwise openings some distance above the bottoms 15 of the transverse openings, opposed jaws mounted in the lengthwise openings and having their adjacent ends tapered toward each other and projecting into one of the transverse openings, a pin extending across 20 one of the lengthwise openings and into

a registering aperture in the adjacent jaw to hold said jaw against endwise movement and a hand lever extending into the other transverse opening and pivotally connected to the adjacent jaw for reciprocating the 25 same toward and from the first-named jaw.

5. A device for opening and closing wire loops and the like comprising a base having lengthwise openings in the upper surface thereof, opposed jaws mounted in the length- 30 wise openings and having their adjacent ends tapered toward each other, a support for the article to be operated upon adjustable toward and from the adjacent ends of the jaws, and means for reciprocating one of 35 the jaws endwise toward and from the other jaw.

In witness whereof I have hereunto set my hand this 5th day of January, 1927.

GEORGE B. CADY.
